DESCRIPTION

U.S. PATENT DOCUMENTS

FIG. 1 is a front view of a display screen or portion thereof with panoramic view in accordance with a first embodiment of the invention;

D526,326 S 8/2006 Matsumoto
D614,634 S 4/2010 Nilsen
D714,818 S * 10/2014 Wang D14/486
D722,609 S 2/2015 Lee
D741,884 S 10/2015 Lee
D843,382 S * 3/2019 Shadforth D14/485
D843,385 S * 3/2019 Ben-Haim D14/485
D847,198 S * 4/2019 Taylor D14/488
D864,235 S * 10/2019 Ben-Haim D14/486
2004/0009459 A1* 1/2004 Anderson G06F 19/3481
434/262

FIG. 2 is a front view of a display screen or portion thereof with panoramic view in accordance with a second embodiment of the invention; and,

2009/0125840 A1 5/2009 Squilla

FIG. 3 is a front view of a display screen or portion thereof with panoramic view in accordance with a third embodiment of the invention.

The broken lines in each FIGURE show the display screen or portion thereof and the remainder of the graphical user interface for the purpose of illustrating environment and form no part of the claimed design.
